Primary Examiner—Ted Shooman*Assistant Examiner*—Carol Rademaker*Attorney, Agent, or Firm*—Harness, Dickey & Pierce, P.L.C.**[57] CLAIM**

The ornamental design for a beverage container, as shown and described.

DESCRIPTION

FIG. 1 is a side elevational view from a corner of the beverage container according to the principles of the present invention, the opposite side being the same as the illustrated side.

FIG. 2 is a side elevational view of the beverage container seen in FIG. 1 when viewed from directly in front of a front panel of the beverage container.

FIG. 3 is a side elevational view from the rear of the beverage container; and,

FIG. 4 is a top plan view of the beverage container.

The broken lines defining the boundaries of the claimed design form no part thereof and the broken lines directed to the environmental structures are for illustrative purposes only and form no part of the claimed design.
